UNITED STATES PATENT OFFICE

HARRY C. FOSTER, OF CONNERSVILLE, INDIANA, ASSIGNOR TO INDIANA LAMP CORPORATION, OF CONNERSVILLE, INDIANA

LAMP CONSTRUCTION

Application filed June 25, 1928. Serial No. 288,163.

This invention relates to a lamp structure particularly adapted for use in connection with automobile lamps or the like.

The principal object of the invention is to provide a lamp structure which will be economical in construction and assembly, while permitting of convenient access to the interior of the lamp for replacement or adjustment of the bulb without requiring the disassembly of the lens, reflector, door rim and sealing gasket. This is of great advantage to the user of the lamp inasmuch as difficulty is usually had with the disassembly and assembly of these various parts merely to give access to the bulb.

By means of this construction the lens, reflector and door rim, as well as the sealing gasket, are securely held together as a unit, which unit may be readily removed to permit the bulb contained within the casing to be replaced or adjusted. This is accomplished by providing a clamping bar which embraces the reflector and clamps the reflector, door rim and sealing gasket together under spring tension, which clamping bar is removably secured direct to the casing for holding the unit therein.

The full nature of the invention will be understood from the accompanying drawings and the following description and claims:

Fig. 1 is a central vertical section through the lamp. Fig. 2 is a section taken on the line 2—2 thereof. Fig. 3 is a rear elevation of the unit removed from the casing.

In the drawings there is shown a lamp having a casing 10, reflector 11, door rim 12, lens 13, sealing gasket 14 and bulb 15. The lens with the sealing gasket is mounted within an outwardly extending flange 16 formed about the periphery of the reflector. They are held in place as a single unit by the clamping bar 17 which embraces the reflector, as shown in Fig. 2. Said clamping bar is formed with outwardly turned ends 18 which hook into the door rim. Secured adjacent thereto there are spring arms 19 which bear against the reflector under spring tension. The tension of the spring arms 19 act to hold the hooks 18 in interlocking position with the

door rim while at the same time forcing the door rim and reflector together for clamping and sealing the lens and gasket therebetween.

The clamping bar 17 is provided with a screw threaded aperture indicated at 20 into which the screw 21 extends, said screw having a head 22 engaging a suitable recess formed in the back of the casing 10. Upon screwing the screw 21 into the bar, the bar is drawn toward the back of the casing so as to cause the door rim 12 to be drawn thereon and secured in closed position.

The bulb 15 is provided with the usual base inserted in a socket 23 which is mounted in a sleeve 24 fixedly secured to the bottom of the casing so as to extend forwardly and upwardly at an angle thereto. A suitable aperture 25 is formed in the lower part of the reflector which is just large enough to permit the bulb 15 to pass therethrough when the unit including the reflector is mounted in place.

The reflector, door rim and lens are secured and held together as a unit by clamping the clamping bar 17 in position. The bulb is mounted in the casing in proper adjusted position. The reflector unit is then positioned within the casing by causing the bulb to pass through the aperture 25, whereupon the clamping bar 17 is engaged by the screw 21 and screwed into position.

Wherein the invention is herein illustrated as relating to a side lamp construction, having the bulb extending up from the lower portion thereof, it will be readily understood that it is also applicable to head lights, wherein the bulb extends forwardly through the center of the reflector. The opening 25 in the reflector is not of such a character as to detract from the reflector surface for practical purposes. The light rays emanating from the bulb which strike that portion of the reflector would be obstructed by the bulb itself under ordinary conditions and the opening is not much larger than the area usually taken up by the lamp socket.

The invention claimed is:

1. In an electric lamp, the combination of a casing, a lamp bulb supported by and within said casing, a reflector member, a lens

member, a door rim member, a clamping bar embracing said reflector and extending about the rear thereof having its free ends engaging said door rim, a spring secured to said bar for engaging the reflector and forcing it under spring tension against said rim whereby said lens will be clamped between said reflector and rim, and means for removably securing said bar to the casing for removably holding the members clamped thereby in position relative to said casing, said reflector having an opening therein to permit passage of the bulb therethrough in the positioning and removal of said members without disturbing the relation of said bulb and casing.

10 2. In an electric lamp, the combination of a casing, a lamp bulb supported by and within said casing, a reflector member, a lens member, a door rim member, a clamping bar embracing said reflector and extending about the rear thereof having its free ends engaging said door rim, a spring secured to said bar adjacent each of the free ends thereof for engaging the reflector and forcing it under spring tension against said rim whereby said lens will be clamped between said reflector and rim, and means for removably securing said bar to the casing for removably holding the members clamped thereby in position relative to said casing, said reflector having an opening therein to permit passage of the bulb therethrough in the positioning and removal of said members without disturbing the relation of said bulb and casing.

15 3. In witness whereof, I have hereunto affixed my signature.

HARRY C. FOSTER.
